(57) **CLAIM**

The ornamental design for an electronic camera, as shown and described.

DESCRIPTION

FIG. 1 is a top, front and side perspective view of an electronic camera showing my new design;

FIG. 2 is a front elevational view thereof;

FIG. 3 is a top plan view thereof;

FIG. 4 is a bottom plan view thereof;

FIG. 5 is a side elevational view thereof from the left of FIG. 2;

FIG. 6 is a side elevational view thereof from the right of FIG. 2; and,

FIG. 7 is a top, front and side perspective view showing the lens in a closed position.

The material shown in broken line illustrates the environment of the present invention.
